HARRY C. RUSSELL, OF NASHUA, NEW HAMPSHIRE.

AUTOMATIC LOCK FOR EXTENSION-LADDERS.

1,113,836.

Specification of Letters Patent.

Patented Oct. 13, 1914.

Application filed November 18, 1913. Serial No. 801,736.

To all whom it may concern:

Be it known that I, HARRY C. RUSSELL, a citizen of the United States, residing at Nashua, in the county of Hillsboro and 5 State of New Hampshire, have invented a new and useful Automatic Lock for Extension-Ladders, of which the following is a specification.

The invention relates to improvements in 10 automatic locks for extension ladders.

The object of the present invention is to improve the construction of automatic locks for extension ladders, more especially the manner of mounting and housing the pivot- 15 ed hook, and to provide a simple and inexpensive device of strong and durable construction adapted to brace and strengthen the extension ladder at the points where the lock is applied.

With these and other objects in view, the invention consists in the construction and 20 novel combination of parts hereinafter fully described, illustrated in the accompanying drawing, and pointed out in the claim hereto appended; it being understood that various 25 changes in the form, proportion, size and minor details of construction, within the scope of the claim, may be resorted to without departing from the spirit or sacrificing 30 any of the advantages of the invention.

In the drawing: Figure 1 is a side elevation of an automatic lock, constructed in accordance with this invention and shown applied to an extension ladder, the pivoted 35 hook being in engagement with one of the rungs of the base ladder. Fig. 2 is a similar view partly in section, the engaging portion of the hook being swung backwardly from its engaging position. Fig. 3 is a longitudinal sectional view, taken substantially on the line 3—3 of Fig. 1.

Like numerals of reference designate corresponding parts in all the figures of the drawing.

In the accompanying drawing in which is 45 illustrated the preferred embodiment of the invention, 1 designates a gravity acting hook pivotally mounted on a slidable extension ladder 2 within a housing 3 thereof and ar- 50 ranged to engage the rungs 4 of a base ladder 5 to which the extension ladder is slid- ably connected in the usual manner. The housing 3 consists of a bar of metal prefer- ably of a width slightly less than the width 55 of the side bar or piece of the extension ladder 2 and having its terminals bent inwardly

at right angles to form abutting end por- 60 tions 6, which fit against the outer face of the adjacent side bar or piece of the exten- sion ladder 2 and space the body portion of the bar from the ladder, as clearly shown in Fig. 3 of the drawing. The housing 3, which is made of relatively heavy material 65 in order to brace the extension ladder at the point where the automatic lock is applied, and secured to the adjacent side of the extension ladder 2 by means of central and end bolts 7 and 8, piercing the housing at the center of the same and at the upper and lower portions thereof. The central 70 bolt, which is relatively heavy, forms a pivot for the gravity hook 1, washers 9 being prefer- ably arranged at the inner and outer faces of the gravity hook to space the same from the side bar or piece of the extension ladder 75 2 and also from the housing, whereby the gravity hook is permitted to swing freely 80 on the pivot bolt. The bolts extend entirely through the side bar or piece of the exten- sion ladder and are preferably provided at 85 their inner ends with nuts, the heads of the end bolts being countersunk in the metal of the housing.

The gravity hook is provided at a point intermediate of its ends with an opening 10 85 for the central pivot bolt, and its upper portion 11 is enlarged and bulged rear- wardly and it forms a weight for throwing the lower portion forwardly into the plane of the rungs of the base ladder. The grav- 90 ity hook is provided at its lower end with a rung receiving recess 12, and it has arms or bills 13 and 14 at the front and back of the recess, the arm 13 being located above and the arm 14 beneath an engaged rung, as 95 illustrated in Fig. 1 of the drawing. When the extension ladder is moved up- 100 wardly on the base ladder, the gravity hook will pass the rungs 4, being swung back- 105 wardly by the same, as illustrated in Fig. 2 of the drawing, the backward movement of the engaging portion of the gravity hook being limited by the lower end bolt. The upper end bolt is also adapted to limit the upward and rearward swing of the engaging 110 end of the gravity hook, so that the latter cannot swing backwardly too far either at the upper or lower portion of the housing and turn completely over to an inoperative position. By this construction, the gravity hook is also maintained by its weighted arm in proper position for automatic engage-

- ment with a rung and free play of the hook on the pivot bolt is permitted. The hook is engaged with a rung by raising the extension ladder sufficiently to carry the hook to 5 a point above the rung to be engaged and the extension ladder is then lowered into engagement with the rung, which is received between the projecting arms or bills 13 and 14.
- 10 The means for mounting the gravity hook substantially houses the same and reinforces or braces the extension ladder and at the same time is devoid of any projections, which might catch on the clothes of the 15 working men and cause a fall.

What is claimed is:—

- The combination with an extension ladder, of a housing consisting of a metallic bar extending longitudinally of one side of 20 the extension ladder and having its terminal portions bent inwardly at right angles and abutting against the extension ladder and spacing the body portion of the bar

from the same, center and end bolts piercing the housing and the adjacent side of the 25 ladder and located at the central and upper and lower portions of the said housing, and a gravity acting automatic hook mounted on the central pivot bolt and having an upper weighted portion and a lower engaging portion, the end bolts forming stops within the housing for limiting the swing of the 30 said lower engaging portion of the hook, whereby the latter is maintained in proper position for automatic engagement with the 35 rung of a base ladder, said bar forming a housing for the hook in both its upright and inverted vertical positions.

In testimony that I claim the foregoing as my own, I have hereto affixed my signature in the presence of two witnesses.

HARRY C. RUSSELL.
